H. C. STOCKDALE
SPRAY GUN SWIVEL MOUNT

2,511,021

Filed March 13, 1946

FIG. 2.

UNITED STATES PATENT OFFICE

2,511,021

SPRAY GUN SWIVEL MOUNT

Harry C. Stockdale, Ravenna, Ohio, assignor to
Food Machinery and Chemical Corporation, a
corporation of Delaware

Application March 13, 1946, Serial No. 653,990

3 Claims. (Cl. 285—97.5)

1

This invention relates to spray gun mountings and it is a particular object thereof to provide a novel and efficient spray gun swivel mount for mounting a spray gun on a hollow mast whereby the gun may be supplied with liquid from the mast, and may be given any desired rotational adjustment relative to said mast about the axis of said mount.

The manner of accomplishing the foregoing object, as well as further objects and advantages, will be made manifest in the following description taken in connection with the accompanying drawings in which:

Fig. 1 is an enlarged fragmentary cross sectional view of the novel liquid conducting swivel connection of the invention, which is shown employed as a mounting of an individual spray gun on a hollow mast for supporting said gun and supplying liquid thereto.

Fig. 2 is a vertical sectional view taken on the line 2—2 of Fig. 1.

Fig. 3 is a fragmentary horizontal sectional view taken on the line 3—3 of Fig. 1.

Referring specifically to the drawings, the invention is there shown as embodied in means for mounting a spray gun on a hollow mast 71.

The mast 71 is provided at spaced intervals with holes 91 in which are welded internally threaded sleeves 92. A spray gun 93 is rotatably mounted on the mast 71 by a hollow spindle 94, the extending threaded shank 95 of which is screwed into one of the threaded sleeves 92.

The spindle 94 has an axial water passage 96, the inner end of which terminates in a square wrench recess 97. Surrounding this recess is a spindle head 98 from the periphery of which an annular cylindrical flange 99 extends in spaced relation with the shank 95 to form an annular packing recess 100. The outer surface of the shank 95 is relieved centrally to form an annular grease pocket 101.

The spray gun 93 may be of any high pressure spray gun construction but preferably has a spray forming mechanism of the type disclosed in my U. S. Letters Patent, No. 2,362,946 issued Nov. 14, 1944. The gun 93 includes a body 108 providing a liquid receiving chamber 109, this being connected to the exterior of the gun by a threaded hole 110 and by a threaded opening 111 concentric therewith. Also formed in the body 108 is a threaded opening 112 in which a gun barrel 113 is screwed, this barrel having a spray forming nozzle 114 provided on its tip.

The body 108 also provides a stuffing box 118 which is coaxial with the barrel 113 and includes

2

a threaded gland 119. Extending through the stuffing box 118 is a spray gun control shaft 120 having threads 121 which have threaded engagement with the gland 119 and a handle 122 on its outer end. Mounted on the inner end of the shaft 120 is a whirl plunger 123 which cooperates with the nozzle 124 to form sprays varying in character, as this whirl plunger is advanced towards or away from the nozzle 114, by 10 rotation of the handle 122, in the manner clearly pointed out in my U. S. Letters Patent aforesaid.

Screwed into the threaded hole 110 is a bearing 130 having an outer shoulder 131 which traps a ring of packing material 132 in an annular recess 133 formed in the body 108 around the outer end of the hole 110, thus forming a liquid tight seal between said bearing and said body.

The bearing 130 has a bore 140 in which the spindle 94 rotatably journals, this bore having 20 an annular grease passage 141 cut therein with which a zerk fitting 142 provided in said bearing communicates.

Extending inward concentrically from the inner end of bearing 130 are cylindrical flanges 143 and 144 between which an annular packing recess 145 is provided. The spindle head flange 98 is adapted to make a close sliding fit with the walls of the recess 145 while the annular flange 144 likewise extends into the annular recess 100. 30 Suitable rings 150 and 151 of packing material are placed in the recesses 100 and 145 so that when the spindle head 98 and bearing 130 are forced axially together, as by liquid pressure within the chamber 109, a fluid tight fit is formed 35 between the nipple and the bearing which prevents the escape of liquid from the chamber 109 between these elements.

The opening 111 is normally closed by a screw plug 152. When this plug is removed, it gives 40 access to the spindle 94 for the insertion of a wrench into the recess 97 for the purpose of screwing the spindle 94 into or out of the threaded sleeve 92.

Extending downwardly from the gun body 108 45 is a lug 153 having an arm 154 from which a pin 155 projects parallel with the axis of the spindle 94. The pin 155 may be utilized for the pivotal connection to the gun 93 of a suitable control member (not shown) for adjusting the 50 rotational position of the gun 93 relative to the mast 71 about the axis of the spindle 94.

I claim:

1. In a spray gun swivel mount, the combination of: a nozzle mount body forming a chamber 55 for receiving liquid under high pressure, there be-

ing a hole in said body opening into said chamber and a discharge passage opening out of said chamber; a tubular bearing element insertable into said hole; means for securing said element in said hole to make a fluid tight connection between said element and said body; a hollow spindle journaling in said bearing and having a head on its inner end which prevents said spindle from being withdrawn outwardly through said bearing, said head being smaller in diameter than said hole in said body; a pair of concentric and cylindrical flanges formed on the inner end of said bearing element, an annular recess being formed between said flanges; and an annular cylindrical flange formed on said spindle head which slideably and rotatably fits into said recess for the purpose of forming a seal between said head and said element.

2. A combination as in claim 1 in which a ring of packing material is disposed in said annular recess to be engaged by said head flange to perfect said seal.

3. A combination as in claim 2 in which an annular recess is formed on said head inside said

10
5

cylindrical head flange, said head recess being adapted to slideably receive the inner cylindrical flange of said bearing element; and a packing ring in said annular head recess, said packing rings being simultaneously brought under pressure by relative axial movement between said element and said spindle.

HARRY C. STOCKDALE.
